UNITED STATES PATENT OFFICE.

WALTER B. KERRICK, OF LOS ANGELES, CALIFORNIA, ASSIGNOR TO KERRICK STEAM MOTORS COMPANY, OF LOS ANGELES, CALIFORNIA, A CORPORATION OF CALIFORNIA.

STEAM-POWER PLANT FOR AUTO VEHICLES.

Application filed March 10, 1921. Serial No. 451,404.

This invention relates to a steam generator of the type disclosed in a co-pending application, Serial Number 605,380, filed by me, Dec. 7, 1922, and particularly pertains to a boiler which is especially applicable for use in auto vehicles for the generation of steam as a source of power in the propulsion of the vehicle.

An object of this invention is to provide a boiler of the above character, in which a series of interchangeable boiler units are employed and so mounted and arranged that they may be readily removed and replaced independent of each other to facilitate repairs and whereby one or more units may be removed without interfering with the operation of the boiler, so that in event one or more of the units should become defective the boiler would not be rendered useless during repairs, but would be capable of being operated with a portion of the units removed.

Another object is to provide a boiler of the type specified, which is so constructed and arranged that supplemental steam generating coils and a steam superheater coil may be employed with the demountable boiler units.

Another object is to provide a boiler embodying steam generating units, steam superheating coils and supplemental steam generating coils; all so disposed relative to the flames in a combustion chamber as not to be subject to sudden temperature changes and so that the content of the coils is subject to gradually increasing temperatures; the steam superheating and supplemental generating coils having adjacent coils in close contact with one another so that in the event of one party taking on an abnormal temperature which would ordinarily result in the burning or the pitting of the tube, the excess heat is absorbed by adjacent coils tending to keep all coils at an equalized temperature.

Other objects will appear hereinafter.

The invention is illustrated in the accompanying drawings, in which:

Figure 1 is a view in vertical section and elevation with parts broken away and with portions removed; showing the fuel line in diagram.

Figure 2 is a horizontal section and plan

view as seen on the line 2—2 of Figure 1 with parts removed.

Figure 3 is a horizontal section and plan view as seen on the line 3—3 of Figure 1.

Figure 4 is a detail in section as seen on the line 4—4 of Figure 3.

More specifically, 5 indicates a boiler unit which is here shown as comprising a vertically disposed cylinder having a cylindrical side wall 6, and bottom and top end walls 7 and 8 fitted with a series of fire tubes 9 arranged interiorly of the cylinder and opening through the end walls. A series of the boiler units is employed in constructing the steam generating plant and which units are preferably disposed in a circle with adjacent units close together but slightly spaced apart. 60 A circular feed-water manifold 10 is located adjacent to the lower ends of the boiler units and each unit is separately and detachably connected to the manifold in open communication therewith. The manifold 10 is preferably arranged to encircle the series of boiler units adjacent to the bottom end walls thereof, so that the units may be readily removed from the underside of the apparatus. The connection between each of the 65 boiler units and the manifold comprises a nipple 11 screwed in the bottom end wall of the units, a goose neck 12 connected to the nipple by a union coupling 13, and a nipple 14 fastened to the manifold and opening 70 thereto and connected to the goose neck by a union coupling 15. 75

Arranged adjacent to the upper ends of the boiler units is a circular steam manifold 16 to which each of the units is detachably connected by a nipple 17 attached to the top end wall 7 of a unit. The boiler units may thus readily be detached from the manifolds by unscrewing a union 13 or 15 and a nipple 17, so that a unit may be removed without 80 disturbing adjacent units, then by capping or plugging the leads to the manifolds, the generator may be operated with the remaining units.

Arranged adjacent to the lower ends of the boiler units and preferably formed to span and close the space encircled by the units is a hydrocarbon burner 18 having a series of suitable burner openings 19 in the upper face thereof located to form a series 85 of flame jets throughout the bottom of the

combustion chamber formed by the boiler units and the burner. This burner is provided with a chamber 20 on its underside with which the burner openings communicate, and leading from this chamber is an intake passage 21 which projects beneath the boiler units and has a flared outer end portion into which a fuel nozzle 22 extends. The inner portion of the passage extends 10 into the chamber and is separated from the latter by a hinged panel 23, which is adapted to open inwardly into the chamber, one of the purposes of this panel being to prevent backfiring into the passage. The upper wall 15 of the inner portion of the passage is formed by the top wall of the burner and is provided with burner openings 24 as shown in Figure 3, which constitutes a pilot burner. The hinged panel 23 is adjusted 20 to be opened automatically by a predetermined pressure difference so that when the supply of fuel to the burner is decreased the induction of air through the intake passage is reduced causing the pressure of the mixture within the burner to decrease in pressure and allow the panel to close, whereupon 25 the mixture passes only through the burner openings 24, to maintain a pilot flame. In this manner only a portion of the burner 30 openings may be in operation at one time according to the degree of temperature it is desired to obtain.

It will be observed that the lower ends of the boiler units, as well as the feedwater 35 manifold, are disposed below the burner 18, so that all connections between the feedwater manifold and the boiler units is not subject to flames or high temperatures, and therefore, do not tend to burn out as might 40 occur were these connections subjected to high temperature. Thus water which normally occupies the space contiguous to the under wall of the boiler unit is maintained at a moderately low temperature and this 45 serves to prevent the natural sediment and precipitations from the water being baked upon the interior walls of the boiler, and leaves the sediment and precipitations in such form as to be readily removable. Naturally, the colder water in the boiler units 50 exists at the lower end portions thereof and in the connections thereto, which are maintained at a comparatively low temperature by reason of the lower ends of the boiler 55 units being located below the burner so that flames from the burner contact with the vertical walls of the boiler units and not with the horizontal end walls thereof.

A fuel generator 25 is positioned immediately above the burner, which is here shown 60 as comprising a series of superimposed pipes 26-27-28-29 of gradually increasing diameters progressing upwardly, the lowermost pipe extending over the pilot burner. This arrangement of the generator pipes

allows for the expansion of the liquid fuel and its changing into gas or vapors, so that the velocity of the contents of these pipes is substantially constant and the area of the pipes relative to the volume contained follows a decreasing ratio. 70

As a means for facilitating cleaning of the generator pipes, they are connected to housings 30-31, fitted with plugs 32 arranged opposite the ends of the pipes and adapted 75 to be removed to permit inserting of pipe cleaners.

The uppermost fuel generator pipe is connected to the discharge nozzle 22 by a pipe 33, and the lowermost generator pipe is connected to a conduit 34 leading from the source of hydrocarbon supply, here shown as comprising a pair of reservoirs 35 and 36, through branch pipes 37-38, fitted with check valves 39 and 40. The reservoir 35 80 is designed to contain kerosene or similar heavy hydrocarbon and to carry a high pressure say of one hundred pounds, and the reservoir 36 is designed to contain gasoline or similar light hydrocarbon under a low 85 pressure; for example, of ten pounds. The check valves 39-40 are preferably of the ball type and are fitted with adjustable stems 41-42, by which the extent of opening of the ball valves may be regulated as 90 occasion may require. The kerosene line is arranged above or beyond the gasoline line and interposed between the check valves is an automatic cut-off valve 43 by which the 95 feed of kerosene may be automatically shut off when steam pressure reaches a predetermined point. The control of the cut-off valve is here shown as effected by a diaphragm 44 arranged in a casing 45 and adapted to bear on a stem 46 to which the 100 valve 47 of the cut-off is affixed; a spring 48 acting on the stem to normally maintain the valve in an open position.

A steam conduit 49 leads from the casing 45 on the side of the diaphragm opposite the valve stem and connects with the steam manifold so that steam pressure in the manifold above a certain point will operate the diaphragm to close the valve in opposition to the spring. By the fuel line 110 arrangement just described, initial heating of the fuel generator may be effected by the use of the lighter hydrocarbon fuel, which fuel will be employed in maintaining a 115 flame in the pilot portion of the burner. 120

Connecting with the steam manifold 16 is a supplemental steam generating coil 50 which extends downwardly into the combustion chamber and has its lower end coil extending upwardly and connected to the 125 steam manifold and has its upper end coil connecting with a pipe 51 leading to a control valve 52, from which a pipe 53 leads to a superheating coil 54, located in the combustion chamber beneath the supplemental 130

steam generating coil; the superheating coil connecting with a pipe 55 leading to an engine or other suitable point of discharge.

The supplemental steam generating coils are arranged in the form of an inverted cone with the adjacent coils contacting each other to reduce the possibility of the coils being overheated, and so that contiguous coils will radiate heat from one to the other to prevent overheating of any one or more coils, and the superheating coils are likewise arranged in the form of an inverted cone with the uppermost coil connected to pipe 53 and its lower coil connected to pipe 55.

Encompassing the boiler units is a casing 56 comprising side walls 57 and top and bottom walls 58 and 59 respectively, and which top and bottom walls are designed to be removable to give access to the interior of the casing. The bottom wall 59 is located below the burner 17 and forms a chamber 60, with which the lower ends of the fire tubes 9 and the boiler units communicate, and which chamber is provided with an opening 61 leading to a stack 62 for carrying off the products of combustion.

The boiler units are designed to be filled with water to a point adjacent their upper ends; the water level preferably being normally maintained in the connection 17 between the boiler units and the steam manifold, or at such point within the boiler units that when water is expanded on initial heating thereof and steam passes to the manifold and from the manifold into the coils 50, a quantity of water will be delivered to the coils 50 so that a number of the lowermost coils 50 will contain water, especially when the boiler is cool.

The products of combustion generated by the burner initially act on the fuel generating tubes, then pass around the superheating coils and along the sides of the boiler units; a portion of the products of combustion impinging on the coils 50 so as to effect an initial generation of steam in said coils on starting the boiler in operation, and also to convert into steam such water as may be delivered to the coils when the boiler is in operation. The coils 50 therefore serve as a supplemental steam generator. As the products of combustion rise a portion thereof is deflected outwardly by the inverted cone structure of the steam generator coils 50 and is caused to contact with the side walls of the boiler units which are disposed close to one another, so that heat is not lost to the side walls 57 of the casing 56. The products of combustion then pass downward through the fire tubes, but at the time of reaching the upper ends of the boiler units to enter the fire tubes are reduced in temperature so that the connections between the units and the steam manifold are not

subject to maximum temperatures, tending to increase the life of those connections.

The products of combustion in passing downward through the tubes heats the water in the boiler units, so that the maximum amount of heat is utilized and are finally discharged at the lower ends of the boiler units at the coldest points of the latter into the chamber 60. When these products of combustion have given up the most of their heat they enter the chamber 60, and come in contact with the feedwater manifold and the walls of the burner body as well, both of which are at practically atmospheric temperatures, with the result that the water in this manifold and the burner body are preheated. As a result the products of combustion are reduced to minimum temperature before escaping through the flue and since a negligible amount of heat escapes through the side walls of the casing it is obvious that a high evaporative efficiency is reached by the steam generating plant. By disposing the burner body within the chamber the mixture of gassified fuel and air from the burner is prevented from precipitating condensed fuel vapors.

The operation of the boiler is as follows: The fuel tanks are filled and subjected to the requisite pressures by means of an air pump or other means not shown. A small quantity of gasoline is admitted to the upper surface of the pilot burner by opening the valve in the priming line. This gasoline is lighted and heats the fuel in the gas generator resulting in a gas being formed which enters the burner through the nozzle and is ignited by the gasoline burning on the upper face of the pilot burner. By means of the regulating stems on the check valves gasoline at pressure is admitted to the generator to supply gas to the burner and as the volume of fuel vapor entering the burner increases the panel swings open and the inner burner is brought into full operation.

The products of combustion follow the path as above described and steam rises from the water in the boiler units and passes through the steam manifold into the coils 50, in which globules of water carried by the steam are converted into saturated steam which may pass to the superheater coils 54 on opening valve 52 where the moisture in the steam is entirely evaporated. When this generating of steam has resulted in a predetermined steam pressure the steam pressure overcomes the tension of the spring controlling the diaphragm to close off the supply of kerosene to the burner, whereupon the pressure in the gasoline tank forces gasoline to the burner. The low pressure of the gasoline results in less fuel entering the burner with the result that the panel closes automatically and the pilot flame only is kept burning to maintain steam pressure.

When steam is required for use the control valve is opened and steam enters the superheater and passes out through the discharge line. Immediately the pressure being reduced the spring raises the diaphragm and the burner is brought into full operation again. It will be observed that the boiler is entirely automatic in its operation and generates steam as fast as it is required to full capacity and all steam is delivered to the discharge pipe in a superheated form and the maximum calorific value of the fuel is utilized in generating steam.

By the arrangement of the boiler units and the steam coils shown, the boilers will serve as a storage for hot water and as purifiers, as sediment will fall below the point of circulation in the boilers and may be readily removed therefrom.

By the construction and arrangement of the various parts of the steam generator herein disclosed repairs may be readily effected; the portions most subject to getting out of order being of easy access. For example, in event leaks occur at the boiler tube and end plate connections, the ends of the tubes may be expanded by a suitable tool without demounting the faulty unit, as by removing the top or bottom walls of the housing the ends of the boiler units will be exposed.

It is to be noted that by connecting the steam manifold to the lower or apex portion of the supplemental generating coils which is disposed closest the burner, the water globules carried into the tubes will be immediately subjected to a maximum heat, and this excess moisture being initially delivered to the portion of the coils subjected to the greatest heat will aid in preventing burning out or overheating of the coils.

The boiler units being disposed with their lower ends located below the combustion chamber, any leakage around the fire tubes at this end of the boiler will not affect the fire and sediment collecting in a boiler unit will be deposited below the point of flame action on the boiler, and in an eddy of relatively still water below the point of circulation thereby greatly reducing incrustation of the boiler. The upper end of the boiler units constituting the tube sheets thereof being disposed in the upper portion of the combustion chamber remote from the burner will not be subjected to the direct action of the flames, will obviate burning out of the tube sheet and tube connections. Furthermore, the connections between the boiler units and the steam manifold by being arranged remote from the burner will be protected against overheating.

By the combination of coil and tubular boiler elements here disclosed with the tube communicating with the upper portion of the boiler the boilers will serve to collect

all sediment so that pure water will be delivered to the coils thereby obviating accumulations of sediment in the coils and clogging thereof.

While I have shown and described a specific embodiment of my invention, I do not limit myself to the exact details of construction or the arrangement of parts shown, but may employ such changes and modifications of the invention as come within the scope of the appended claims.

I claim:

1. In a steam power plant, a series of boiler units fitted with fire tubes, a steam manifold arranged adjacent to the upper ends of said units, a water manifold arranged adjacent to the lower ends of said units, each of said units being detachably connected to said manifolds, a housing encompassing the boiler units and manifolds, a heating element arranged adjacent to the lower ends of said boiler units and an arrangement whereby the heat generated by said heating element will pass upwardly to the upper ends of said boiler units, then flow downwardly through the fire tubes of said units, and a supplemental steam generating coil connecting with said steam manifold and projecting downwardly toward the heating element.

2. In a steam power plant, a series of boiler units fitted with fire tubes, a steam manifold arranged adjacent to the upper ends of said units, a water manifold arranged adjacent to the lower ends of said units, each of said units being detachably connected to said manifolds, a housing encompassing the boiler units and manifolds, a heating element arranged adjacent to the lower ends of said boiler units and an arrangement whereby the heat generated by said heating element will pass upwardly to the upper ends of said boiler units, then flow downwardly through the fire tubes of said units, and a supplemental steam generating coil connecting with said steam manifold and projecting downwardly toward the heating element; a superheating coil interposed between the heating element and the steam generating coils and a valve connection between said steam generating coils and the superheating coil.

3. In a steam generator, the combination of a burner having an upper face formed with burner openings, a plurality of spaced vertical boiler units arranged around said burner with the lower end portions thereof extending below the upper face of said burner and with the major portions thereof extending above the burner, means connecting the lower end portions of adjacent boiler units to form a water connection throughout the series of units on a plane below the top of the burner, a steam manifold, means whereby each of said manifold units is sep-

arately connected at its upper end to said steam manifold, a supplemental steam generator coil in the form of an inverted cone arranged within the space surrounded by 5 said boiler units and having its lowermost convolution connected to said steam manifold, and a control valve to which the upper convolution of said coil leads; said coil operating as a flame spreader to direct flames 10 against said boiler units.

4. In a steam generator, the combination of a burner having an upper face formed with burner openings, a plurality of spaced vertical boiler units arranged around said burner with the lower end portions thereof extending below the upper face of said burner and with the major portions thereof extending above the burner, means for delivering water to the lower end portion of 15 each of said boiler units, a steam manifold to which the upper end of each of said units connects, and a supplemental steam generator coil in the form of an inverted cone arranged within the space surrounded by the 20 boiler units and having its lowermost convolution connected to said steam manifold; said coil serving as a flame spreader to direct flames against and between said spaced vertical boiler units.

5. In a steam generator, a series of vertical boiler units arranged in a circle, a steam manifold connecting said boiler units, a supplemental steam generating coil arranged in the form of an inverted cone having 25 adjacent convolutions abutting whereby heat may radiate from one coil to the next, said coil depending below the upper ends of said boiler units and having its lower coil connected to said manifold; said coil operating as a flame spreader to direct flames 30 against said boiler units, a burner located below said coil, and a superheating coil interposed between the first named coil and burner connected to the uppermost convolution of said first named coil.

6. In a steam generator, a burner, a series of vertical firetube boiler units arranged around said burner, a steam manifold, detachable connections between said manifold 35 and each of said boiler units, a supplemental steam generator comprising a coil of tubing

arranged in the form of an inverted cone and depending into the space surrounded by said boiler units, the lowermost coil of which connects with the steam manifold 45 whereby water may be delivered from said boiler units to said generator, and a superheater coil interposed between said generator coil and the burner and connecting with the uppermost coil of the generator coil; 50 said generator coil serving to direct flames against said boiler units.

7. In a steam generator, a burner, a series of vertical firetube boiler units arranged around said burner, a supplemental steam 55 generating coil arranged in the space encircled by said boiler units, a communication between the lowermost coil of said generator and the upper portions of said boiler units whereby water and vapors may be delivered from said generator, a discharge pipe 60 connecting with the upper coil of said generator, a superheating coil interposed between the burner and the generating coil 65 communicating with the upper portion of the latter, and a valve for controlling the communication between said coils.

8. A steam generator comprising a combustion chamber enclosed by side walls, a top wall and a bottom wall; a burner in said combustion chamber, a series of vertical firetube boiler units arranged around said burner having their lower ends opening below the bottom wall of the combustion chamber and their upper ends opening to the combustion chamber, a water manifold connecting the water spaces in the lower ends of said boiler units, a steam manifold connecting the upper ends of the water spaces in said boiler units, a supplemental steam generating coil arranged in the space surrounded by said boiler units having its lowermost coil communicating with said steam manifold, said coil being in the form 80 of an inverted cone and serving to direct products of combustion outwardly toward said boiler units, and a superheating coil arranged between said generating coil and the burner communicating with the upper portion of said generating coil.

WALTER B. KERRICK.
